UNITED STATES PATENT OFFICE.

JOHN DUDLEY BALL, OF PONTIAC, ILLINOIS, ASSIGNOR OF ONE-HALF TO DAVID NORSTEDT, OF CHICAGO, ILLINOIS.

SKIRT-GAGE.

No. 928,239.

Specification of Letters Patent.

Patented July 20, 1909.

Application filed October 23, 1908. Serial No. 459,253.

To all whom it may concern:

Be it known that I, JOHN DUDLEY BALL, a citizen of the United States, residing at Pontiac, in the county of Livingston and State 5 of Illinois, have invented a new and useful Skirt-Gage, of which the following is a specification.

My invention relates to gages, whereby the length of a skirt may be regulated and 10 marked, and the main object of the invention is to provide a gage, whereby the edge of the skirt may be turned over to form a level hem at any required distance from the floor.

15 A further object is to provide a gage having a gage bar over which the hem may be turned, which bar may be slipped out of the hem as the same is completed.

20 A still further object is to simplify the construction of gages of this character and to provide a gage which shall be easily adjusted to any required height, which will stay rigidly set wherever adjusted, and which will have a maximum of strength 25 with a minimum of parts.

25 In the drawings:—Figure 1 is a perspective view of my skirt gage. Fig. 2 is a top view of the same, partly in section. Fig. 3 is a fragmentary detail, showing the clamping 30 end of the gage bar partly in section.

Similar reference numerals designate corresponding parts in all the figures of the drawings.

35 2 designates a weighted base of any desired character, and 3 a vertical standard graduated in any preferred manner, preferably by inches and quarter inches.

40 4 designates the horizontal gage bar, which is curved in a horizontal plane to conform to the curvature of the edge of a skirt. This bar is made of a relatively flat bar of metal, which at its end is bent around upon itself to form an eye 5 and a prolongation 6 extending beyond the eye and parallel with 45 the main portion of the gage bar. The eye 5 loosely surrounds the standard so that the bar may be readily shifted up or down as desired. A clamping screw 7 passes through the prolongation 6 and into and through the 50 main portion of the gage bar, which when turned, acts to close or open the eye. When the eye is closed, the arm is held rigidly on

the standard, and when the clamp screw is loosened, the resiliency of the metal causes the eye to open, thus permitting the gage 55 bar to be readily adjusted.

In operation, the gage bar 4 is set on the standard to the height at which it is desired the skirt should clear the floor, after which the bottom of the skirt is turned up 60 over the arm inside of the skirt and pinned or basted into place. The person being fitted should then turn partially, allowing the finished portion of the garment to slide off the gage bar. The same method should 65 then be continued until the entire circumference of the skirt has been turned up.

The advantages of my invention reside particularly in its simplicity, durability and ease of operation. With my gage bar there 70 is no necessity of marking the skirt with chalk, which thus injures the cloth. By reason of the gage bar being made of flat metal, which is bent around the standard, greater rigidity is secured, and the gage bar 75 itself is not likely to be bent, which is liable to occur where a round metal bar is used for this purpose. My gage bar being set on edge and the flattened portion of the bar contacting with the standard and surrounding the same, the gage bar has a firm bearing on the standard, and the bar itself has a 80 rigidity which prevents its giving or yielding vertically. This is of great importance 85 in this class of devices as the accurate turning up of the bottom of the skirt depends upon the gage bar being horizontal at all times. It will be noted that my construction is extremely simple and may be very 90 easily manufactured.

From the foregoing, it is thought that the construction, operation and many advantages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is:—

A skirt gage comprising a base, a vertical

graduated standard, a flattened gage bar,
the rear end of said bar being returned upon
itself to form a resilient eye surrounding
the standard, and a clamp screw passing
5 through said returned portion of the bar,
engaging with the main portion thereof, and
acting to close the eye on said standard or
permit the same to expand.

In testimony, that I claim the foregoing
as my own, I have hereto affixed my sig- 10
nature in the presence of two witnesses.

JOHN DUDLEY BALL.
